DRIVING ARRANGEMENT FOR THE SPINDLES OF CENTRIFUGAL SPINNING, TWISTING, AND ANALOGOUS MACHINES

Edmund E. Feather, Riddlesden, Keighley, England, assignor to Prince-Smith & Stells Limited, Burlington Shed, Keighley, England, a British company

Application March 3, 1949, Serial No. 79,438
In Great Britain March 18, 1948

12 Claims. (Cl. 57—105)

This invention relates to a centrifugal spinning, twisting and analogous machine having a bobbin carriage provided with means whereby it is elevated automatically for the purpose of doffing the spinning containers collectively on completion of the spinning or other operation in question, and also having a driving arrangement wherein the spinning containers are tape driven by means of a central rotary cylinder, or a driving shaft upon which are mounted balanced driving pulleys, in association with counter-weighted tension pulleys and guide pulleys. A machine having the above features is disclosed in the Wright Patent No. 2,450,622 dated October 5, 1948. The present invention has for its object to obviate the detrimental results liable to ensue in the event of the breaking of any of the tapes driving the spinning containers.

It is well known that, in the event of a container of a centrifugal spinning or like machine of the above kind coming to rest prior to the transfer of the spun material to a bobbin, the annulus of material tends to collapse within the container owing to the absence of the necessary centrifugal force to maintain it in position, and forms a tangled mass within the container; and unless this is observed and the mass removed as soon as possible after the affected container comes to rest normal unwinding or doffing of the material in the remaining containers will be prevented by the inability of a bobbin to enter an affected container and, consequentially, the material in all the unaffected containers will be irrecoverable and wasted.

The present invention is designed to guard against the occurrence of such a contingency.

According to the invention, a centrifugal spinning, twisting or analogous machine, wherein the front carriage is elevatable automatically for doffing purposes and having the aforesaid driving arrangement for the spinning containers is provided with mechanism whereby breakage of a driving tape, or equivalent element for rotating the spinning containers, causes unwinding of the material spun in all the containers to be initiated automatically, the momentum of the rotating containers completing the unwinding operation.

To this end electro-magnetically controlled means are associated actuatable with the tensioning elements of the tape-driving mechanism and with the front carriage release mechanism.

The current necessary to energise the electro-magnetic element or elements may be derived from the power supply in the case of an elec-

trically-driven machine, or from a suitable extraneous source in the case of a mechanically driven machine, and the invention is applicable either to a single-sided or double-sided machine.

The invention as applied to the machine of the aforesaid patent No. 2,450,622 is illustrated by way of example in the accompanying drawings in which:

Figures 1, 2 and 3 are semi-diagrammatic sectional views of the driving mechanism of a pair of mutually opposite spinning containers of a double-sided electrically driven centrifugal spinning machine, the driving tape being omitted in Figures 2 and 3, and the respective figures being illustrative of the relative positions occupied by the parts of the mechanism, respectively, under normal spinning conditions, after the breakage of the driving tape, and when the affected containers are rendered inoperative in order to permit spinning to be re-commenced without the necessity for immediately replacing the broken tape.

Referring firstly to Figure 1 of the drawings, 1, 1 are two vertical members and 2 is an integral transverse member of one of the intermediate frame members which together with two end-stands (not shown) support fixedly two longitudinal rails 3, 3, located on opposite sides of the machine and having secured thereto a series of projecting horizontal brackets 4, 4, in each of which is mounted a bearing housing 5 above which is arranged a whorl 6 rotatably connected to the neck of an inverted cup-shaped spinning container 7, all of which parts are known per se.

The front carriage of the machine comprises the usual vertically reciprocable frame having at the top an angularly movable rockshaft 8 supported by vertical rack pillars such as 9 each slidably in a guide bracket such as 10 integral with a casting 11 having a flanged base 12 resting on the bottom rail 13.

To the rockshaft 8 is secured a series of bobbin pegs such as 14 each supporting a bobbin 15 in axial alignment with one of the aforesaid spinning containers 7, and parallel with and below the rockshaft 8 a pinion shaft 16 is supported in bearings on the main frame of the machine (not shown) and has keyed to it pinions such as 17 corresponding in number to and meshing with the rack pillars 9, and an operating handwheel 18 is keyed to one end of the pinion shaft 16. Each rack pillar guide bracket 10 is formed integrally at its upper end with a rearwardly projecting tubular boss 19 in which

is slidably mounted a spring-urged plunger-latch 20 whereof the forward extremity normally enters a recess 21 in the back of the rack pillar 9 and whereof the rearward extremity is formed with an eye 22 to which is connected one end of a cord 23 which is passed below a fixed cylindrical abutment 24 and is carried upwardly to and over a second fixed cylindrical abutment 25 from which the cord 23 extends to and is secured to latch-withdrawing means to be referred to hereafter.

Each pair of mutually opposite whorls 6 is encircled by a common endless driving tape 26 which passes over a guide pulley 27, under a driving cylinder 28 (or a driving pulley) carried by a driving shaft 29, and over a tape-tensioning pulley 30 running freely on an arbor 31 journaled in the upper end of one limb of a cranked tension lever 32 whereof the lower end is movable angularly about an arbor 33 and is formed with an integral tail member 34 carrying a counterweight 35. The tension lever 32 has pivoted to it at 36 a biased detent 37 whereof the nose 38 is engageable with a toothed sector 39 integral with an extension 40 of which the boss 41 is mounted stationarily on the arbor 33, the extension 40 having a pin 42 projecting laterally from its free end and engageable by either one of two notches 43, 44, formed in a link 45 pivoted at 46 to a short arm 47 integral with the tension lever 32.

A longitudinal rockshaft 48 extends the full length of the machine and is supported in bearings carried by brackets 49 secured to the transverse frame members 2, and, at each pitch, this rockshaft 48 has keyed to it a downwardly extending actuator arm 50 having a lug 51 at its free extremity projecting into alignment with the path of angular movement of the tension lever 32.

At one end of the rockshaft 48, or at any desired intermediate point in its length, a trip finger 52 is keyed adjacent to a casing 53 containing a limit switch comprising a pair of contacts 54, 55, adapted to be bridged by a blade 56 and a pair of contacts 57, 58, adapted to be bridged by a blade 59. 60 is a spring-controlled switch-actuating plunger carrying a roller 61 adapted to be contacted by a laterally projecting lug 62 integral with the free extremity of a trip finger 52, the switch casing 53 being mounted on a fixed bracket 63 and the pairs of contacts 54, 55, 57, 58, being connected by conductors 64, 64A, in circuit, respectively with a pair of solenoids 65, 65, appropriate to the respective bobbin front carriages.

Each solenoid includes a core 66 terminating in a plunger or tappet 67 the weighted lower extremity 68 of which is located above the flattened rear extremity 69 of a tappet arm 70 fulcrumed on a shaft 71 alongside a lever 72 also fulcrumed on said shaft and having a horizontal slot 73 in which a stud 74 is mounted adjustably, the aforesaid cord 23 being secured to the upper end of the lever 72.

Normally, the circuit controlled by the limit switch in the casing 53 is closed and the trip finger 52 is maintained out of contact with the roller 62 by means of an arm 52A keyed to the rockshaft 48 and having its free end anchored by a spring 52B to the transverse frame member 2.

75 is a constantly rotating member or disc carrying a projecting peg 76 into the path of movement of which the forward extremity 70A 75 means, a driving arrangement for a spinning

of the tappet arm is adapted to be moved as hereinafter explained, and rotatable with the disc 75 is a worm wheel 77 engaged drivably by a worm 78 keyed on the lower end of a vertical worm shaft 79 on the upper end of which is keyed another worm 80 meshing with a worm wheel 81 rotatable with a spur wheel 82 forming part of a train of gearing 83, 84, 85, 86, 87 and 88, receiving motion from the driving shaft 29.

Under spinning conditions the various parts are in the positions shown in Figure 1, and immediately a tape 26 breaks the resistance offered by it to the tensioning pulley 30 ceases and, under the influence of the counterweight 35 the tension lever 32 is moved angularly in a clockwise direction as viewed in Figure 2 of the drawings and its upper end is brought into contact with the lug 51 on the actuator arm 50 which is moved angularly in a counterclockwise direction and turns the rockshaft 48 so as to raise the trip finger 52 and bring the lug 63 thereon into contact with the roller 62 on the switch plunger 61, as shown in Figure 2, pressing the plunger inwardly of the switch and opening the circuit controlled thereby by moving the blades 56 and 59 from the appropriate contacts.

The result of this is to de-energize the solenoids 65, 65, the weighted plungers 67 of which fall by gravity on to the flat ends 69 of the tappet arms 70, the forward ends 70A of which, owing to the continued rotation of the discs 75, are wiped by pegs 76 into contact with the studs 74 carried by the levers 72 which latter levers are thereby moved angularly towards the center line of the machine each thus exerting a pull upon the attached cord 23 and withdrawing the corresponding plunger-latch 20 from its recess 21 in the rack pillar 9, releasing the front carriages which are immediately automatically elevated and insert the bobbins 15 into the spinning containers 7. The unwinding of the contents of all the unaffected spinning containers 7 is then completed by the momentum of the spinning containers 7.

The aforesaid angular movement of the tension lever 32 raises the link 45 until the pin 42 on the extension 40 is engaged by the recess 44 which together with the detent 37, 38, serves to maintain the parts in the position shown in Figure 2 while the broken tape is being replaced.

After the replacement of the broken tape the rockshaft 48 is returned by spring 52B to the running position shown in Figure 1, permitting the closure of the limit switch and the re-energization of the solenoids.

If, however, it is not desired or not convenient to replace the broken tape immediately, the nose 38 of the detent 37 is disengaged from the sector 39 and the tension lever 32 is moved counterclockwise as viewed in Figure 3 until the pin 42 on the extension 40 is engaged by the recess 43 in the link 45, by which means the tensioning pulley 30 is supported clear of the actuator arm 50 and the affected containers 7 remain inactive while the spinning operation continues in the remaining containers of the machine.

The link 45 serves also to prevent the tension pulley 30 falling into contact with the guide pulley 27.

70 What I claim is:

1. In a centrifugal spinning, twisting and analogous machine having tape-driven spinning containers and an automatically elevatable bobbin carriage provided with releasable retaining

container comprising, an endless driving tape serving to rotate said container, a tensioning pulley supported by said driving tape, and mechanism associated with said tensioning pulley connected operatively to said releasable retaining means in such manner as to effect the release of said bobbin carriage in the event of the breakage of said driving tape.

2. In a centrifugal spinning, twisting and analogous machine having tape-driven spinning containers and an automatically elevatable bobbin carriage provided with releasable retaining means, a driving arrangement for a spinning container comprising, an endless driving tape serving to rotate said container, a tensioning pulley supported by said driving tape, and mechanism associated with said tensioning pulley and with electro-magnetic controlling means connected operatively to said releasable retaining means in such manner as to effect the release of said bobbin carriage in the event of the breakage of said driving tape.

3. In a centrifugal spinning, twisting and analogous machine having tape-driven spinning containers and an automatically elevatable bobbin carriage provided with releasable retaining means, a driving arrangement for a spinning container comprising, an endless driving tape serving to rotate said container, a driven member to drive said driving tape, a tensioning pulley supported by said driving tape, and a switch actuator coaligned with said tensioning pulley, said switch actuator being associated with electro-magnetic means connected operatively to said releasable retaining means in such manner as to effect the release of said bobbin carriage in the event of the breakage of said driving tape.

4. In a centrifugal spinning, twisting and analogous machine having tape-driven spinning containers and an automatically elevatable bobbin carriage provided with releasable retaining means, a driving arrangement for a spinning container comprising, an endless driving tape to rotate said container, a driven member to drive said driving tape, a tensioning pulley supported by said driving tape, said tensioning pulley being carried by a tension lever, a switch actuator coaligned with said tension lever, a trip member connected to said switch actuator and said trip member being associated with electro-magnetic means connected operatively to said releasable retaining means in such manner as to effect the release of said bobbin carriage in the event of the breakage of said driving tape.

5. A driving arrangement for spinning container of a centrifugal spinning, twisting and analogous machine as claimed in claim 3, characterised by means to offer positive support to said tensioning pulley in the event of the breakage of said endless driving tape.

6. A driving arrangement for a spinning container of a centrifugal spinning, twisting and analogous machine as claimed in claim 5, characterised by means to offer positive support to said tensioning pulley in the event of the breakage of said endless driving tape.

7. In a centrifugal spinning, twisting and analogous machine having tape driven spinning containers and an automatically elevatable bobbin carriage provided with releasable retaining means, a driving arrangement for a spinning container comprising, a tape-tensioning pulley mounted on an angularly movable tension lever, a pivoted switch actuator arm co-

aligned with said tension lever and connected operatively to an angularly movable trip finger, a switch controlling an electro-magnetic circuit and located adjacent to said trip finger, a solenoid arranged in circuit with said switch, said solenoid having a weighted core, and a tappet arm located adjacent to and operable by said solenoid core to effect the release of said bobbin carriage in the event of the breakage of a driving tape.

5 8. In a centrifugal spinning, twisting and analogous machine having tape-driven spinning containers and an automatically elevatable bobbin carriage provided with releasable retaining means, a driving arrangement for a spinning container comprising, a tape-tensioning pulley mounted on an angularly movable counterweighted tension lever, an angularly movable switch actuator arm co-aligned with said tension lever and connected operatively to an angularly movable trip finger, a switch controlling an electro-magnetic circuit and having a member projecting adjacent to said trip finger, a solenoid arranged in circuit with said switch and provided with a depending weighted core, and an angularly movable tappet arm located adjacent to and operable by said depending weighted core to effect the release of said bobbin carriage retaining means in the event of the breakage of a driving tape.

10 9. In a centrifugal spinning, twisting and analogous machine having tape-driven spinning containers and an automatically elevatable bobbin carriage provided with releasable retaining means, a driving arrangement for a spinning container comprising, a tape-tensioning pulley mounted on an angularly movable tension lever, an angularly movable switch actuator arm co-aligned with said tension lever and connected operatively to an angularly movable trip finger, a switch controlling an electro-magnetic circuit and located adjacent to the path of movement of said trip finger, a solenoid arranged in circuit with said switch and provided with a weighted core, a tappet arm located adjacent to and operable by said solenoid core in the event of the breakage of a driving tape, and means movable into contact with said tension lever for offering positive support thereto during the replacement of a broken tape.

15 10. In a centrifugal spinning, twisting and analogous machine having tape-driven spinning containers and an automatically elevatable bobbin carriage provided with releasable retaining means, a driving arrangement for a spinning container comprising, a tape-tensioning pulley mounted on an angularly movable counterweighted tension lever, an angularly switch actuator arm co-aligned with said tension lever and connected operatively to an angularly trip finger, a switch controlling an electro-magnetic circuit to a solenoid, a member projecting from said switch into the path of angular movement of said trip finger, an angularly movable tappet arm operable by said solenoid in the event of the breakage of a driving tape, and means for offering positive support to said tension lever during the replacement of a broken tape.

15 11. In a centrifugal spinning, twisting and analogous machine having tape-driven spinning containers and an automatically elevatable bobbin carriage provided with releasable retaining means, a driving arrangement for a spinning container comprising, a tape-tensioning pulley

normally supported by a driving tape and mounted on an angularly movable tension lever, an angularly movable switch actuator arm located in the path of angular movement of said tension lever and connected operatively to an angularly movable trip finger, a switch controlling an electro-magnetic circuit to a solenoid and located adjacent to said trip finger, said solenoid having a weighted core, a tappet arm operable by said solenoid core in the event of the breakage of a driving tape, means for offering positive support in one position to said tension lever during the replacement of a broken tape, and further means for offering positive support in a second position to said tension lever to maintain said lever out of the path of angular movement of said actuator arm.

12. In a centrifugal spinning, twisting and analogous machine having tape-driven spinning containers and an automatically elevatable bobbin carriage provided with releasable retaining means, a driving arrangement for a spinning container comprising, a tape-tensioning pulley normally supported by a driving tape and mounted on an angularly movable counterweighted tension lever, an angularly movable switch actuator arm located in the path of angular move-

ment of said tension lever and connected operatively to an angularly movable trip finger, a switch controlling an electro-magnetic circuit to a solenoid, a member projecting from said switch into the path of angular movement of said trip finger, an angularly movable tappet arm operable by said solenoid in the event of the breakage of a driving tape, means for offering positive support in one position to said tension lever during the replacement of a broken tape, and further means for offering positive support in a second position to said tension lever to maintain said lever out of the path of angular movement of said actuator arm in order to cause the spinning container affected by said broken tape to remain immobile while the remaining spinning containers continue to operate.
